UNITED STATES PATENT OFFICE.

ERNEST H. FAUST, OF LEXINGTON, GEORGIA.

FOLDING IRONING-BOARD.

1,032,196.

Specification of Letters Patent.

Patented July 9, 1912.

Application filed February 15, 1912. Serial No. 677,651.

To all whom it may concern:

Be it known that I, ERNEST HENRY FAUST, a citizen of the United States, residing at Lexington, in the county of Oglethorpe and 5 State of Georgia, have invented certain new and useful Improvements in Folding Ironing-Boards, of which the following is a specification.

This invention appertains to improvements in ironing boards and has for its primary object to provide a substantial device which may be readily folded into a small compass for storing away out of use.

Another object of my invention is to provide an ironing board with a tripod support comprising means for readily locking the same in extended operative position, and other means coöperating with that first mentioned to lock the tripod against the 20 board in its folded inoperative position.

For a full understanding of the present invention, reference is to be had to the following description and to the accompanying drawings, in which—

25 Figure 1 is a side elevation of my device in position for use, the dotted lines showing its folded position. Fig. 2 is a side elevation of the board in folded locked position, being partly broken away to show clearly 30 the locking member. Fig. 3 is a partial view in side elevation and partly broken away. Fig. 4 is a detail sectional view on the line 4—4 of Fig. 2. Fig. 5 is a partial end elevation.

35 Throughout the following detail description and on the several figures of the drawings, similar parts are referred to by like reference characters.

Referring now to the drawings, a device 40 constructed in accordance with my invention consists of a board proper designated 1, having secured on its under surface at the enlarged end portion thereof a cleat or block 2. Hinged to the inner end of the block 2 45 is a pair of diverging supporting legs 3, connected at their upper portion by means of a transverse bar 5, said legs being arranged to extend toward the enlarged end of the board proper 1.

50 Secured to the outer edge of the block 2 as by means of mortising, is a depending arm 6, which is preferably bifurcated to receive the upper end of a supporting leg 7 pivotally mounted on the pintle 8. The leg 55 7 is formed with a shoulder 7' near its

upper portion, against which the transverse bar 5 is adapted to abut when the device is in extended position for use, and the leg 7 is furthermore provided with a recess 9 slightly below the shoulder 7'. 60

Centrally mounted on the transverse bar 5 is a locking member comprising a lug 10 having a screw threaded shank 11 for securing said locking member in the transverse bar 5 aforesaid. Independent locking 65 means are provided consisting of a locking plate 12 revolvably mounted on the shank 11 and formed with diametrically opposing hooks 12' which are adapted to engage in the staples 13 when the board is folded, one 70 of said staples being secured in the board proper 1 while the other is secured to the leg 7.

When the board is in operative position, the legs 3 are moved downwardly and the 75 leg 7 is also moved downwardly until the transverse bar 5 abuts against the shoulder 7' when the lug 10 is engaged in the recess 9, thus securely locking the device in position for use. The leg 7 preferably extends 80 to a point approximately beneath the smaller end of the board in order to form a substantial support when pressure is exerted on this end of the ironing board proper.

From the foregoing, it will be apparent 85 that the tripod support comprising the legs 3 and 7 may be readily folded against the board proper 1 by disengaging the lug 10 from the recess 9 and be secured to said board by a slight rotation of the locking 90 plate 12 to engage the hooks 12' in the staples secured in the leg 7 and board 1 as hereinbefore described, and the device may then be readily stored away to occupy a 95 minimum amount of space.

Having thus described the invention, what is claimed as new is:

1. In an ironing board, the combination of a board proper, a pair of legs hinged intermediate its ends, a connecting member 100 between the legs, a leg hingedly connected to the board adjacent the pair of legs aforesaid and having a recess therein, said leg being adapted to extend between said pair of legs, locking means for said board comprising a locking member carried by the connecting member aforesaid and adapted to hold the board in extended operative position, a locking plate pivotally mounted on said locking member, and means on the 110

board and leg engageable with the ends of the locking plate to hold said board in folded inoperative position.

2. In an ironing board, the combination
5 of a board proper with a tripod support comprising a pair of legs hinged to said board intermediate its ends, a transverse bar connecting said legs, and a leg pivoted to one end of the board adapted to extend
10 between the legs aforesaid and having a recess formed therein; staples secured in the board proper and on said leg; a locking member secured to the bar consisting of a

lug adapted to engage in the recess aforesaid to hold the board in extended operative 15 position, and independent locking means comprising a double hook locking plate mounted on the lug and adapted to engage in the staples to lock said board in folded inoperative position.

In testimony whereof I affix my signature in presence of two witnesses.

ERNEST H. FAUST.
